[57] CLAIM

The ornamental design for a notebook computer, as shown and described.

DESCRIPTION

FIG. 1 is a perspective view of a laptop computer showing my new design with the display screen shown in the open position;

FIG. 2 is a front elevational view thereof on an enlarged scale;

FIG. 3 is a top plan view thereof;

FIG. 4 is a rear elevational view thereof illustrated with the display screen in the closed position;

FIG. 5 is a right side elevational view thereof;

FIG. 6 is a left side elevational view thereof;

FIG. 7 is a front elevational view thereof;

FIG. 8 is a top plan view thereof; and,

FIG. 9 is a bottom plan view thereof.

FIG. 1.

FIG. 2.

FIG. 3

FIG. 5.

FIG. 6.

FIG. 4.

FIG. 7.

FIG. 8.

FIG. 9.

UNITED STATES PATENT AND TRADEMARK OFFICE
CERTIFICATE OF CORRECTION

PATENT NO. : Des. 351,377

DATED : October 11, 1994

INVENTOR(S) : Scott S. Yu

It is certified that error appears in the above-identified patent and that said Letters Patent is hereby corrected as shown below:

On the title page, item [73] should read as follows:

Assignee: Arche Technologies
Fremont, California

Signed and Sealed this
Twentieth Day of June, 1995

Attest:

BRUCE LEHMAN

Attesting Officer

Commissioner of Patents and Trademarks
